FIG. 5

UNITED STATES PATENT OFFICE.

FREDERICK GOERTZ, OF NEWARK, NEW JERSEY, ASSIGNOR TO AUGUST GOERTZ & CO.,
A CORPORATION OF NEW JERSEY.

SANITARY SHIELD FOR TELEPHONE APPARATUS.

1,244,977.

Specification of Letters Patent. Patented Oct. 30, 1917.

Application filed October 25, 1916. Serial No. 127,536.

To all whom it may concern:

Be it known that I, FREDERICK GOERTZ, a citizen of the United States, residing at Newark, in the county of Essex and State 5 of New Jersey, have invented certain new and useful Improvements in Sanitary Shields for Telephone Apparatus; and I do hereby declare the following to be a full, clear, and exact description of the invention, 10 such as will enable others skilled in the art to which it appertains to make and use the same, reference being had to the accompanying drawings, and to characters of reference marked thereon, which form a part of 15 this specification.

The present invention relates, generally, to a sanitary device or attachment in the form of a shield, which, when not in use, may be carried by an individual, but when 20 to be used is readily attached by him in removable relation over the speaking-opening of the transmitter of a telephone, and may also, if desired, be detachably arranged over the sound-opening of the receiver of 25 the telephone.

The present invention, therefore, has for its main purpose or object, the provision of a sanitary means, in form of a shield, or cover, adapted to be detachably mounted 30 over the speaking-opening of the transmitter, or the sound-opening of the receiver of a telephone, with a view of providing a sanitary device which can be used at will by the person telephoning, is readily removable by such person, after having telephoned, and is carried away by such person for future use in connection with another telephone-apparatus.

With these main ends in view, the invention has for its further object to provide a sanitary shield or cover which has many advantages, and is especially adapted for use with public telephones, so that a person desiring to use such public telephone 45 need not hesitate for fear of contagion due to unsanitary conditions of the telephone-apparatus.

With the various objects of this invention in view, the said invention consists, primarily, in the novel sanitary shield or cover-attachment for telephone-apparatus, such as hereinafter more fully set forth and then finally embodied in the clauses of the claim which are appended to and which form an 55 essential part of the following specification.

The invention is clearly illustrated in the accompanying drawings, in which:—

Figure 1 is a front elevation of a telephone-apparatus showing in connection therewith, and also in front elevation, a 60 sanitary shield or cover slipped over the rim of the transmitter, and illustrating one embodiment of the principles of the present invention, and Fig. 2 is a side elevation of the telephone - transmitter and sanitary 65 shield attached or mounted in front of the speaking-opening of the transmitter.

Fig. 3 is a rear view of the sanitary shield or cover, detached from the telephone-apparatus, and Fig. 4 is a transverse vertical 70 section of the same, said section being taken on line 4—4 in said Fig. 3.

Fig. 5 is a similar section of a slightly modified construction of sanitary shield or cover, but still embodying the principal features of the present invention.

Similar characters of reference are employed in the above described views, to indicate corresponding parts.

Referring now to the said figures of the 80 drawings, the reference-character 1 designates any usual form of telephone, in the present case a telephone-stand, the base of which is indicated by the reference-character 2. The reference-character 3 indicates 85 the usual telephone-transmitter, 4, the pivoted circuit-cut-out lever, and 5 the telephone-receiver supported upon said lever.

The sanitary shield or cover is adapted for use in connection with any telephone-apparatus, as has been heretofore stated, and the same consists, essentially, of a face-plate, as 6, usually of metal, which is provided with an opening, as 7. Upon its upper marginal portion 8, the said face-plate 90 6 is usually made arc-shape, being a semi-circle, which conforms to the general contour of the marginal edge of the transmitter 3 or the receiver 5. The lower portion of the said face-plate 6 extends downwardly, substantially as shown at 9 in Figs. 1, 4 and 5, to thereby provide an apron-effect for readily slipping or arranging the device in front of the transmitter or receiver, as will be presently more fully described. Surrounding the curved portion 8 and the straight marginal portions 10 and 11 of the said face-plate is a rearwardly extending flange-like member 12 formed with a slightly curved and inwardly extending 105 110

2
 retaining edge-member 13, providing a suitable retaining means for retaining the sanitary shield in its mounted position upon the marginal edge-portions of the transmitter 5 or receiver, when the device is slipped into its mounted relation over the speaking-opening of the transmitter or the sound-opening of the receiver, as will be clearly evident.

- 10 Fitted upon the inner face of the said face-plate, and conforming to the general marginal contour of the latter, is a disk or plate, as 14, of a thin and suitable material, a thin sheet of celluloid being practical for 15 the purposes of my present invention, the said disk or plate being preferably provided with any number of suitably disposed small holes or perforations, as 15. The perforated portion of the said disk or plate, as shown 20 in the several figures of the drawings, extends directly across the back of the opening 7 in the said face-plate 6, so as, except for the perforation 15, to provide a closure for said opening 7, and still not interfere with 25 the conveying of the vibratory sound-waves to the transmitter or from the receiver.

Back of the said disk or plate 14 is a suitable fabric, as 16, or other suitable arrangement of matter, treated with a disinfectant or germ-destroying material, the said elements 14 and 16 being retained in position against the back of the said plate 6 by means of the previously-mentioned flange-like member of the plate 6 and one or more 30 clamping lugs, as 17, extending from the marginal edge of the said plate and bent over upon the back of the element 16, substantially in the manner shown in Fig. 3 of the drawings.

- 40 In some cases an additional backing, as 18, which may be provided with holes or perforations, as 19, may be arranged upon the rear face of the fabric or other disinfecting element 16, as clearly illustrated in Fig. 5 45 of the drawings, the various elements being suitably secured upon the rear face surface of the said face-plate 6, in substantially the same manner as indicated in the construction illustrated in Figs. 3 and 4 of the drawings.

50 As shown, the shield may be of greater width at its lower portion than at its upper portion, thereby permitting the shield to be more readily slipped into its position upon 55 the transmitter 4 or upon the receiver 5. This wider arrangement of the shield at the lower end thereof is also essential in that it permits of the use of the shield with different sizes of transmitters or receivers

which, in practice, have been found to vary 60 somewhat in diameter.

From the foregoing description of my present invention it will be clearly seen, that I have provided a simply constructed attachment for telephone-apparatus, which is 65 of such size and weight that it can be readily carried in the pocket without inconvenience, and when it is desired to use a telephone, may be quickly placed over the transmitter, (and an additional device may be placed 70 over the receiver,) thus safeguarding the person using the telephone against coming in contact with parts of the telephone that may be unsanitary or germ-carrying, the danger from such unclean surfaces being 75 more especially prevalent in public telephones.

I claim:—

1. A sanitary shield for telephone-apparatus comprising a face-plate formed with 80 an opening, said face-plate formed at its upper edge with a supporting-means conforming to part of the marginal edge-portion of the telephone-transmitter, and at its lower edge-portion having an unobstructed apron-like part extending beneath the lower portion of the transmitter when in position thereon and being of greater width at its lower portion than at its upper portion, a germ-preventing and destroying element 85 connected with said face-plate.

2. A sanitary shield for telephone-apparatus comprising a face-plate formed with an opening, said face-plate formed at its upper edge with a supporting-means conforming 95 to part of the marginal edge-portion of the telephone-transmitter, and at its lower edge-portion having an unobstructed apron-like part extending beneath the lower portion of the transmitter when in position thereon and being of greater width at its lower portion than at its upper portion, a germ-preventing and destroying element connected with said 100 face-plate for detachably attaching said face-plate, said supporting means consisting 105 of a rearwardly and inwardly extending flange-like element extending along a portion of the marginal edge of the said face-plate, and adapted to be brought into sliding engagement with a portion of the marginal 110 edge of the transmitter.

In testimony, that I claim the invention set forth above I have hereunto set my hand this 20th day of October, 1916.

FREDERICK GOERTZ.
